[57] **CLAIM**

The ornamental design for a squirrel-proof bird feeder, as
shown.

DESCRIPTION

FIG. 1 is a front elevational view of the squirrel-proof bird
feeder of the present invention;

FIG. 2 is a rear elevational view of the squirrel-proof bird
feeder of FIG. 1;

FIG. 3 is a left side elevational view of the squirrel-proof
bird feeder of FIG. 1;

FIG. 4 is a right side elevational view of the squirrel-proof
bird feeder of FIG. 1;

FIG. 5 is a top plan view of the squirrel-proof bird feeder of
FIG. 1; and,

FIG. 6 is a bottom plan view of the squirrel-proof bird feeder
of FIG. 1.
